UNITED STATES PATENT OFFICE.

MOSES ESSEGIAN, OF EAST CAMBRIDGE, MASSACHUSETTS.

DESIGN FOR A CORNER-SHIELD FOR SUIT-CASES OR SIMILAR ARTICLES.

41,607.

Specification for Design.

Patented July 25, 1911.

Application filed February 1, 1911. Serial No. 606,054. Term of patent 7 years.

To all whom it may concern:

Be it known that I, MOSES ESSEGIAN, a citizen of the United States, residing at East Cambridge, county of Middlesex, State of Massachusetts, have invented a new, original, and ornamental Design for Corner-Shields for Suit-Cases or Similar Articles, of which the following is a specification, reference being had to the accompanying drawing, forming a part thereof, in which drawing a perspective view of a corner-shield is shown embodying my new design.

I claim:

The ornamental design for a corner shield for suit cases or similar articles as shown.

In testimony whereof I affix my signature, in presence of two witnesses.

MOSES ESSEGIAN.
